Primary Examiner—Ralf Seifert

(57) **CLAIM**

I claim the ornamental design for the key chain, as shown.

DESCRIPTION

FIG. 1 is a perspective view of the invention in an unfolded condition.

FIG. 2 is a front elevational view of the inventive key chain design.

FIG. 3 is a back elevational view of the inventive key chain design.

FIG. 4 is a top view of the inventive key chain design.

FIG. 5 is a bottom view of the inventive key chain design.

FIG. 6 is a left view of the inventive key chain design; and,

FIG. 7 is a right side view of the inventive key chain design. A flexible key chain upon which a keyring may be attached. The keychain comprises the stitching from a baseball, and may include a tab, shown in phantom, upon which a logo or other indicia may be disposed.

It being understood that the broken lines are for illustrative purposes only.
